US00D928734S

(12) **United States Design Patent** (10) Patent No.: **US D928,734 S**
(45) Date of Patent: ** *Aug. 24, 2021

(54) **HEADSET**

(71) Applicant: **Apple Inc.**, Cupertino, CA (US)

(72) Inventors: **Robert Brunner**, Glen Ellen, CA (US);
Christopher Kuh, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/713,080**

(22) Filed: **Nov. 13, 2019**

Related U.S. Application Data

(60) Continuation of application No. 29/634,460, filed on Jan. 22, 2018, now Pat. No. Des. 867,327, which is a continuation of application No. 29/568,227, filed on Jun. 16, 2016, now Pat. No. Des. 809,477, which is a continuation of application No. 29/527,761, filed on May 21, 2015, now Pat. No. Des. 760,688, which is a continuation of application No. 29/490,833, filed on May 14, 2014, now Pat. No. Des. 732,503, which is a continuation of application No. 29/471,109, filed on Oct. 28, 2013, now Pat. No. Des. 709,860, which is a (Continued)

CLAIM

The ornamental design for a headset, as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a right side view thereof;

FIG. 6 is a left side view thereof; and,

FIG. 7 is a top view thereof.

The broken lines in the figures show portions of the headset that form no part of the claimed design.

1 Claim, 7 Drawing Sheets

Related U.S. Application Data

division of application No. 29/410,584, filed on Jan. 9, 2012, now Pat. No. Des. 692,410.
